UNITED STATES PATENT OFFICE.

PLATO G. EMERY, OF CHICAGO, ILLINOIS.

FIXTURE FOR WINDOW-SHADES.

1,170,742.

Specification of Letters Patent.

Patented Feb. 8, 1916.

Application filed July 25, 1913. Serial No. 781,068.

To all whom it may concern:

Be it known that I, PLATO G. EMERY, a citizen of the United States, residing at Chicago, county of Cook, State of Illinois, have 5 invented a certain new and useful Improvement in Fixtures for Window-Shades, and declare the following to be a full, clear, and exact description of the same, such as will enable others skilled in the art to which it 10 pertains to make and use the same, reference being had to the accompanying drawings, which form a part of this specification.

The present invention relates to shades or curtains having at one end a stick provided 15 with heads adapted to travel in grooves in the window frame and has for its object to produce a device which shall be efficient and reliable in operation, durable, convenient to assemble and operate, and at the same time 20 simple and inexpensive in construction.

The various features of novelty whereby 25 my invention is characterized will herein-after be pointed out with particularity in the claims; but, for a full understanding of my invention and of its objects and advantages, reference may be had to the following 30 detailed description taken in connection with the accompanying drawings, wherein:

Figure 1 is a central longitudinal section 35 taken through one end of a shade stick arranged in accordance with one form of my invention; Fig. 2 is a view partly in front elevation and partly in section of the parts shown in Fig. 1, the parts being illustrated in the positions which they occupy when the 40 heads are retracted; Fig. 3 is a front view on a smaller scale of a complete stick; Fig. 4 is a front elevation of the central portion of a stick embodying a modified form of my invention; Fig. 5 is a central longitudinal section 45 taken at right angles to the plane of Fig. 4; Fig. 6 is a view corresponding to Fig. 5, illustrating a further modification; Fig. 7 is a view similar to Fig. 6 with the 50 parts occupying the releasing positions; Fig. 8 is a central longitudinal section through the middle portion of the stick containing a still further modification; Fig. 9 is a view similar to Fig. 8, showing the parts 55 in the releasing positions; Fig. 10 is a transverse section taken between the finger pieces of a stick arranged in accordance with a further modification of my invention; and Fig. 11 is an elevation of a modified form of friction block.

In the ordinary street car or railway car

construction there are grooves at the sides of the window frames into which extend heads arranged on the ends of the window shades or curtains, the grooves and heads 60 serving to interlock the free ends of the curtains or shades with the window frames so as to guide the shades or curtains and prevent them from swinging inwardly or outwardly or from flapping. The heads also 65 usually serve as frictional holding devices for preventing the shades from being wound up upon their spring rollers. Finger pieces are provided for retracting the heads somewhat when it is desired to raise or lower the 70 shade, but this retraction of the heads should not be sufficient to permit the heads to pass out of the grooves in the window frames.

One of the features of my invention has to do particularly with the control of the 75 heads on the ends of a shade stick, so as to permit them ordinarily to be retracted sufficiently to release their frictional grip at the sides of the window without danger of completely disengaging them from their grooves 80 and also making it possible, when desired, to retract the heads far enough to release them from the grooves.

Reference being had to the first three figures of the drawings, 1 represents a tubular 85 shade stick having at the ends suitable heads, 2, which may conveniently be mounted by providing them with stems slidably fitting into the open ends of the tubular stick. At the middle of the tube there is formed an 90 opening, 4, through which extend finger pieces, 5, of any suitable kind. Each head is connected to one of the finger pieces in any suitable way, conveniently by means of a rod, 6, one end of which is attached to the 95 head and the other end screw-threaded into the finger piece. Behind each head may be placed a suitable spring, 7, tending normally to force the head outwardly.

Between the two finger pieces is a suitable 100 transverse abutment, 8, which may conveniently be part of a suitable escutcheon plate, 9, arranged over the opening 4 in the stick. On each finger piece is a projection, 10, extending laterally from one side in the direction of the other finger piece. The parts are so arranged that when the two finger pieces are grasped and pressed together as is usually done when it is desired to retract the head sufficiently to permit the shade to be 105 raised or lowered easily, the projections 10 strike against the abutment 8, limiting the 110

movement of the finger pieces toward each other and the extent to which the heads are retracted; the parts being so proportioned that the heads cannot be retracted far enough to release them from their grooves before the finger pieces are arrested by the abutment.

When for any reason it is desired to release the stick from interlocking engagement with the window frame, the finger pieces are pressed laterally at the same time that they are drawn together, so as to permit the projections 10 to pass on one side of the abutment. In the arrangement shown the parts are so arranged that by pressing the finger pieces inwardly as they are drawn together, the projections will pass beneath the abutment without being arrested by them. This additional retracting movement of the heads through a distance equal to the width of the abutment is sufficient to release the heads from the grooves in the window frame. This control of the heads does not interfere in any way with the longitudinal adjustment of the heads which permits a stick to be fitted nicely into frames varying somewhat in width, because the heads may be adjusted in and out by simply screwing the rod 6 farther into or partially unscrewing them from the finger pieces.

In Figs. 4 and 5 I have illustrated a somewhat different arrangement in which the finger pieces 11 are normally arrested by a movable abutment, 12, arranged between them. In the particular arrangement illustrated, the abutment is made of greater length than width and is normally held with its greater dimension in alignment with the two finger pieces by means of a torsion spring 13. Normally, therefore, the finger pieces may be pressed toward each other so as partially to retract the heads on the stick, complete retraction being prevented by the abutment. When the abutment is turned around through an angle of 90 degrees against the tension of its spring, its shorter dimension is brought into alignment with the finger pieces and therefore the finger pieces may be brought more closely together than during normal conditions, making it possible to effect a complete release of the heads from the window grooves.

In Figs. 6 and 7 I have combined the features of the two forms already described, there being an abutment normally in position to engage with the projections, 10, on the finger pieces, and this abutment being movable so as to permit the finger pieces to approach each other more closely. In this form of my invention, the abutment comprises a tubular button, 14, slidably upon a stationary guide, 15, in the stick and normally pressed outwardly by a spring, 16,

surrounding the post or guide 15. The button is provided with an outwardly-projecting stem, 17, by means of which the button may be pressed inwardly out of the paths of the projections 10.

70

In Figs. 8 and 9 I have illustrated a still further form of my invention in which the finger pieces 18 have wedge shaped projections, 19, provided with blunt ends. Each projection serves as an abutment for the other in the normal operation of the shade. That is, when the finger pieces are pressed toward each other, their approach is arrested when the two abutments engage with each other. When it is desired completely to retract the heads, the finger pieces are canted slightly, or one is pressed inwardly or the other outwardly as they approach each other and then, instead of the end of one projection striking the end of the other projection, the two projections slide past each other as indicated in Fig. 9.

75

In Fig. 10 I have shown still another arrangement, there being a hinged abutment, 20, in the position occupied by the abutment 8 in Fig. 1. Normally the operation is the same as with the arrangement shown in Fig. 1. When it is desired to release the stick from the window frame, the abutment is swung out of the way and the finger pieces are free to approach each other more closely than when the abutment is in its working position.

80

My invention includes a second feature which adds to the simplicity, efficiency and durability of my improved device. In the ordinary fixture, the heads on the stick are provided with anti-friction rollers as indicated at 25 in Figs. 1, 2 and 3 and with some means between the rollers for effecting a frictional engagement between the stick and the window frame. In accordance with my invention this latter means takes the form of a small block, 26, polygonal in form and secured in the head by a pin or journal, 27, passing through the center of the polygon and at right angles to the axis of the stick. In the arrangement shown in Figs. 1 and 2 each head is provided with a single friction block arranged in alignment with the stick while in the arrangement shown in Fig. 3 each head has two of these blocks as indicated at 28. The blocks are so proportioned and so located on the heads that one side of the block projects slightly beyond a line tangent to both of the anti-friction rollers; so that when the stick is horizontal the blocks engage with the window frames and hold the anti-friction rollers slightly away from the frame. Each friction block has only a comparatively small surface in contact with the window frame so that the pressure per unit area is much greater than in the case of the elongated friction shoe usually employed.

130

Consequently a firm grip is obtained on the window frame and the slipping which occurs when the ordinary long shoe becomes polished through wear is obviated. There is of course more or less wear on the working faces of the blocks and, by making the blocks polygonal and supporting them rotatably, the same face will not always be the working face, but one face after another will naturally come into play so that the wear will be distributed over all of the faces. Of course, if desired, the blocks may be supported in such a way that they will not turn freely and in this event each face will be subjected to wear until the block is intentionally turned so as to bring another face into the working position.

In Fig. 11 I have illustrated a modified form of block, 29, having the shape of a pointed star. The action of this block is the same as that heretofore described except that the wearing surfaces are smaller.

While I have illustrated and described only a few simple forms of my invention, I do not desire to be limited to the exact structural details thus illustrated and described; but intend to cover all forms and arrangements which fall within the terms employed in the definitions of my invention constituting the appended claims.

I claim:

1. In combination, a shade stick, a head mounted at the end of the stick so as to be movable lengthwise of the stick, a rod extending from the head into the stick, an actuating device on the rod, and a device in the path of the actuating device and adapted to limit its movement in the direction of the length of the stick, one of said devices being normally yieldingly held in alinement with the other device and being movable in a direction to bring it out of alinement with the other and afford the actuating device an increased range of movement.

2. In combination, a shade stick, a head mounted at the end of the stick so as to be movable lengthwise of the stick, a rod extending from the head into the stick, an actuating device on the rod, and a stop device normally adapted to engage with the actuating device at a predetermined point in the movement of the latter in the direction of the length of the stick, one of said devices being normally yieldingly held in alinement with the other device and being movable transversely of the stick to permit the actuating device to pass beyond said predetermined point.

3. In combination, a hollow shade stick 60 having an opening through the side, a head mounted at one end of the stick so as to be movable lengthwise of the stick, a rod extending from the head into the stick, a finger piece on the rod extending through said 65 opening, and a stop device adapted in normal operation to engage with a shoulder on the finger piece to arrest the movement of the finger piece in the direction of the length of the stick, the parts being so proportioned 70 that the finger piece may be moved transversely of the stick to bring said shoulder out of alinement with the stop to afford the finger piece an increased range of movement.

4. In combination, a tubular shade stick 75 having an opening through the side, a head mounted at the end of the stick so as to be movable lengthwise of the stick, a small rod extending from the head into the stick, a finger piece extending from said rod through 80 said opening, said finger piece having a projection extending laterally toward the end of said opening farthest from said head so as to engage with the edge of said opening in the normal operation of the finger piece and 85 limit its movement, and the parts being so proportioned as to permit the inner end of the rod to be sprung laterally far enough to let said projection clear the aforesaid edge of the opening.

5. In combination, a shade stick, a head mounted at the end of the stick so as to be movable lengthwise thereof, a rod extending from the head into the stick, an actuating device on the rod, and a device in the path 95 of the actuating device and adapted to limit its movement in the direction of the length of the stick, the parts being so constructed and arranged that one of said devices is normally held yieldingly in alinement with the 100 other device and is movable relatively thereto in a direction to bring them out of alinement with each other and afford the actuating device an increased range of movement.

6. In combination with a shade stick, of a head on the end of said stick, rollers at the ends of said head, and a polygonal friction block journaled on said head between said rollers so as to be rotatable about an axis 110 transverse to the stick.

In testimony whereof, I sign this specification in the presence of two witnesses.

PLATO G. EMERY.
